[57] CLAIM

The ornamental design for a twist-on electrical connector, as shown and described.

DESCRIPTION

FIG. 1 is a top and side perspective view of the twist-on electrical connector showing our new design;

FIG. 2 is a side elevational view thereof, all other side elevational views being the same;

FIG. 3 is a top plan view thereof; and,

FIG. 4 is a bottom plan view thereof.

FIG.1.

FIG.2.

FIG.3.

FIG.4.
